Inventor:
Donald Thomas Allen
Son of
C. W. Allen

UNITED STATES PATENT OFFICE.

DONALD THOMAS ALLEN, OF MILWAUKEE, WISCONSIN, ASSIGNOR TO PRIME MFG. CO.,
OF MILWAUKEE, WISCONSIN.

PHONOGRAPH.

Application filed January 2, 1925. Serial No. 129.

To all whom it may concern:

Be it known that I, DONALD THOMAS ALLEN, a citizen of the United States, and resident of Milwaukee, in the county of Milwaukee and State of Wisconsin, have invented certain new and useful Improvements in Phonographs; and I do hereby declare that the following is a full, clear, and exact description thereof.

10 This invention relates to phonographs.

Objects of this invention are to provide a portable phonograph which may be folded into a compact formation, which is provided with a horn of ample size having a relatively 15 large mouth or outlet portion, and to provide a phonograph which is so constructed that a slide carried by the cover closes the outer end of the horn and protects such horn against entrance of dirt or other harmful 20 material.

Further objects are to provide a portable phonograph which is of extremely simple construction, which may be cheaply produced, and which is effective in operation.

25 An embodiment of the invention is shown in the accompanying drawings, in which:—

Figure 1 is a vertical sectional view through the phonograph showing it in closed position, such view corresponding to a section on the line 1—1 of Figure 2.

Figure 2 is a front view partly broken away showing the phonograph open.

The phonograph is substantially of box like construction and comprises a base member 1 having a rear wall 2, side walls 3 and a front wall 4. A top 5 is provided and may be of substantially the same general contour as the bottom portion. This top has downwardly extending marginal portions 6, the rear of which is hinged to the rear wall 2 of the bottom portion.

35 The bottom is provided with a horizontal partition 7 upon which the tone arm 8 is swivelly mounted in the usual manner. Any suitable type of phonograph motor is mounted in the bottom and drives the record-carrying disk 18, as may be seen from Figure 2. The tone arm opens into the base portion adjacent a rear corner thereof. A curving 40 wall 17 is positioned vertically between the partition 7 and the bottom wall 2 of the bottom half of the device and extends to the front wall 4. The vertical wall, it will be

noted from Figure 2, forms with the opposed side wall 3 a gradually increasing 55 space which constitutes a horn.

It is to be particularly noted from Figure 4 that the front wall 4 is cut out to provide an elongated opening 9 forming the mouth of the horn. A curved deflector plate 10 (see Figure 1) is positioned immediately below the outlet portion of the tone arm 8 and may be secured either at its upper or its lower end or in fact at both to the bottom half of the device.

It is to be noted from Figure 1 that the partition 7 stops short of the front wheel 4 a slight distance and thus provides a slot. A flap or closure plate 11 is hingedly carried by the front marginal wall 6 of the top 70 and is adapted to slide into this slot and to close the opening 9 in the front wall 4 and thus close the mouth of the horn. A pair of guiding strips or posts 12 are positioned adjacent the lateral edges of the partition 7 and form braces between the bottom 1 and such partition, as clearly shown in both figures. These strips 12 or posts form guides 75 against which the flap 11 slides. Preferably, the upper front portions of the guides 12 are slightly tapered to facilitate the removal of the flap 11, as may be seen from Figure 1. If desired, the top 5 may be provided with a threaded pin 13 adapted to receive and store records 14, such records 80 being held in place by means of a thumb nut 15.

In using the device the top is opened and the flap 11 is thus withdrawn from the mouth of the horn and hangs downwardly, 90 as shown in Figure 2. Thereafter, the device is used in the usual manner without having any obstruction for the horn.

It is apparent that if it is desired to lessen the volume of the sound emitted by the phonograph that any suitable plate may be slipped into the slot between the partition 7 and the front wall 4 and may thus regulate the volume of the sound.

When the device is closed the mouth of 100 the device is completely protected and the horn is also closed, as shown in Figure 1, and the device may be carried by means of the handle 16.

Although the invention has been described 105 in considerable detail, it is to be under-

stood that the invention may be variously embodied and is, therefore, to be limited only as claimed.

I claim:

- 5 1. A portable phonograph comprising a box like bottom portion having an upper horizontal partition, a record-carrying disk positioned above said bottom partition, a tone arm swivelly mounted adjacent a rear corner of said partition and opening into said bottom portion, a horn carried within said bottom portion, and having a deflector plate carried below said tone arm, said bottom portion having an open front wall communicating with said horn, said partition stopping short of said front wall, a cover hinged to said bottom portion and a flap carried by said cover and adapted to slide between said partition and said front wall to close the aperture in said front wall.
- 10 2. A portable phonograph comprising a box like bottom portion having an upper horizontal partition, a record-carrying disk
- 15
- 20

positioned above said horizontal partition, a tone arm swivelly mounted adjacent a rear corner of said partition and opening into said bottom portion, a horn carried within said bottom portion, and having a deflector plate carried below said tone arm, said bottom portion having an open front wall communicating with said horn, said partition stopping short of said front wall, a cover hinged to said bottom portion and a flap carried by said cover and adapted to slide between said partition and said front wall to close the aperture in said front wall, said bottom portion having supporting posts positioned below the front edge of said partition adjacent its sides and forming guides for said flap.

In testimony that I claim the foregoing I have hereunto set my hand at Milwaukee, in the county of Milwaukee and State of Wisconsin.

DONALD THOMAS ALLEN.
